COMBINATION SWING HINGE AND JOINT

George Yoshio Ueda, Honolulu, Territory of
HawaiiApplication July 3, 1940, Serial No. 343,821
In Japan July 6, 1939

5 Claims. (Cl. 220—37)

This invention relates generally to closures such as covers, caps, doors, windows etc., and more particularly to mountings therefor.

An object of this invention is to provide a combined swing hinge and joint by which a closure can be mounted in a manner to be supported in various open positions for different utilitarian purposes.

Another object of the invention is to provide a swing hinge and joint by which a closure can be operatively and detachably connected to a receptacle or other support in such manner that the closure can be supported therefrom in an inclined open position to drain accumulated moisture from the closure into the receptacle as its contents, such as food, are being cooked, the closure also being supportable in a generally horizontal position at one side of the receptacle to provide a rest for culinary utensils, and being suspendable vertically at one side of the receptacle for convenient pouring or drinking of the contents.

With these and other objects in view, the invention resides in the combinations and arrangements of elements as set forth in the following specification and particularly pointed out in the appended claims.

In the accompanying drawings,

Figure 1 is a vertical sectional view of the invention applied to a receptacle such as a cooking vessel;

Figure 2 is an enlarged fragmentary sectional view of the operative connection between the cover and receptacle;

Figure 3 is an enlarged fragmentary view of the aforesaid operative connection in front elevation;

Figure 4 is a fragmentary view of the upper portion of the receptacle in side elevation, with the cover thereof in closed position;

Figure 5 is a vertical sectional view of the receptacle with a tray or carrier structure embodied therein and operatively connected to the cover;

Figure 6 is a perspective view of another form of receptacle embodying this invention;

Figure 7 is a fragmentary detail sectional view of a portion of the receptacle shown in Figure 6;

Figure 8 is a perspective view of a third form of receptacle embodying the invention.

Referring specifically to the drawings and particularly to Figures 1 to 4, inclusive, this form of the invention comprises a round receptacle R such as a metal cooking vessel, having a closure or cover C, and operatively and detachably connected to the receptacle by means of a mounting element M co-actable with a hinge member H.

The element M comprises a semi-circular wire bail 10, the ends of which are in-turned to form trunnions 11 pivotally mounted in diametri-

cally opposed openings in the receptacle in juxtaposition to its lip 12.

The hinge member H is constructed from sheet metal and is of generally U-form with one branch 5 secured by rivets 14 to the cover. The bight portion of the member H loosely engages the bail 18 between right and left hand stop elements 15 having lateral detents 16 spaced sufficiently to prevent hinging movement of the member H on the bail and adapted to selectively co-act with the member to support the cover in the upwardly and outwardly inclined position shown at a in full lines in Figure 1 wherein the cover is clear of the mouth of the receptacle. To support the cover in this position, the cover is tilted laterally on the bail, as shown in Figure 3, to one side or the other so that one detent or the other will be disposed in the path of downward hinging movement of the cover on the bail. Any 10 moisture accumulating on the inside of the cover when in this position will drain into the receptacle.

The other branch 18 of the member H is curved outwardly to a location for engagement with the 15 side wall of the receptacle when the member H is disengaged from the detents 16 and the cover is swung downwardly about the bail as an axis, to the substantially horizontal position shown at b in broken lines in Figure 1, wherein the cover 20 is inverted and provides a convenient support or rest for spoons, knives or forks which are used on the contents of the receptacle during or after the cooking operation.

Projecting from the inner side of the cover 35 at a central location thereon is a hook 20 adapted to co-act with the bail 10 in supporting the cover from the receptacle lip 12 in the downwardly and outwardly inclined position shown at c in broken lines in Figure 1. The hook 20 can be attached 40 to a chain 21 or other flexible member leading from a tray or strainer 22 in the receptacle, so as to raise and lower the tray according as the cover is opened or closed, as shown in Figure 5.

In the position c of the cover, the latter is supported sufficiently clear of the receptacle mouth for convenient access to the contents, and can be readily closed by disengaging the hook 20 from the lip 12, with a combined swinging movement of the bail 10 about its axis on the receptacle, and hinging movement of the cover about the bail.

The cover can also be suspended vertically by the bail 10 as shown at d in broken lines in Figure 1, so as to be disposed at the side of the receptacle and permit the contents of the latter to be poured therefrom without interference by the cover, or the contents can be conveniently drunk from the receptacle with the cover in this position.

At diametrically opposed places at an angular distance of ninety degrees from the hinge member H are other hooks 25 which are also adapted to co-act with flexible members such as the chain 21 in operatively connecting the cover to a tray 22 to raise and lower the latter as aforesaid. By the provision of the U-shaped hinge member H the cover can be readily detached from the bail 10 for cleaning purposes and for handling of the receptacle independently of the cover.

Reference will now be had to Figure 6 which illustrates the invention applied to a round receptacle such as can be advantageously used as a condiment holder. This receptacle can be provided with a side handle 30 and has its top wall 31 detachably secured to the body 32 of the receptacle by teats 33 on a depending flange 34 of the wall, springing into recesses 35 in the body.

The wall 31 is provided with a series of perforations 36 the central one of which is of larger diameter than the others. Conical or other shaped closure pins 37 project from the inner side of a cover C' for co-action with the perforations 36, the central pin being longer than the others to act as a pilot in co-axially relating the cover and receptacle.

By means of a hinge member H' similar to the hinge member H, the cover is hinged to a mounting element M' in the form of a bail 10a having suitable trunnions 11a entering diametrically opposed openings in the body 32 to pivotally connect the bail to the receptacle.

The bail 10a co-acts with the hinge member H' to enable the cover C' to be suspended at one side of the cover in an unobstructing position for dispensing of the contents through the perforations 36, and to be readily detached from the receptacle. In the closed position of the cover, the pins 37 seal the openings 36 to prevent contamination of the contents.

Reference will now be had to Figure 8, which illustrates a rectangular receptacle R2 to which is hinged connected a closure C2 by means of a mounting element M2 functioning in the manner of the bails 10 and 10a and composed of links 19b pivotally connected at 40 to the receptacle at locations medially between opposite sides thereof and in juxtaposition to the open side thereof. The other ends of the links are pivotally connected at 41 to the cover C2 at locations adjacent one edge thereof. Along a medial line, hooks 20b project from the inner side of the cover and are adapted to be hooked over the inner edge of the receptacle to support the cover in the inclined open position shown in Figure 3. Chains 21b can be connected to these hooks, and trained over hooks 42 on the inside of the receptacle, for connection to a tray or other carrier 43 in the receptacle so as to raise or lower the tray according as the cover is opened or closed, whereby to render the contents conveniently accessible when the cover is opened.

What is claimed is:

1. In combination, a receptacle; a cover for the receptacle; a mounting element pivotally connected to the receptacle; means hingedly connecting the cover adjacent the perimeter thereof, to said mounting element at a location sufficiently spaced from the pivotal connection of the element to the receptacle that the cover can be swung about the pivotal and hinged connections to occupy various positions to one side or the other of the receptacle; and means on the first means co-actable with the receptacle to

support the cover in an inverted and substantially horizontal position at one side of the receptacle for the support of articles on the cover.

2. In combination, a receptacle; a cover for the receptacle; a mounting element pivotally connected to the receptacle; means hingedly connecting the cover adjacent the perimeter thereof, to said mounting element at a location sufficiently spaced from the pivotal connection of the element to the receptacle that the cover can be swung about the pivotal and hinged connections to occupy various positions to one side or the other of the receptacle; and means on the cover co-actable with the rim portion of the receptacle to support the cover in an outwardly and downwardly inclined position relatively to the receptacle with a portion of the cover overlying the receptacle for access to the contents of the latter.

3. In combination, a receptacle; a cover for the receptacle; a mounting element pivotally connected to the receptacle; means hingedly connecting the cover adjacent the perimeter thereof, to said mounting element at a location sufficiently spaced from the pivotal connection of the element to the receptacle that the cover can be swung about the pivotal and hinged connections to occupy various positions to one side or the other of the receptacle; means on the cover co-actable with the rim portion of the receptacle to support the cover in an outwardly and downwardly inclined position relatively to the receptacle with a portion of the cover overlying the receptacle for access to the contents of the latter; a tray in the receptacle; and means co-actable with the last means and tray by which the latter is raised or lowered in the receptacle according as the cover is opened or closed.

4. In combination, a receptacle; a cover for the receptacle; a mounting element pivotally connected to the receptacle; means hingedly connecting the cover adjacent the perimeter thereof, to said mounting element at a location sufficiently spaced from the pivotal connection of the element to the receptacle that the cover can be swung about the pivotal and hinged connections to occupy various positions to one side or the other of the receptacle; and a hook member projecting from the inner side of the cover substantially medially thereof, adapted to engage the rim portion of the receptacle for co-action with the mounting element in supporting the cover in an outwardly and downwardly inclined position.

5. In combination, a receptacle; a cover for the receptacle; a bail pivotally mounted on the receptacle; a generally U-shaped hinge member secured to the cover at the edge thereof and detachably connected to the bail to provide a hinge joint between the two for co-action in enabling the cover to be swung about the hinge joint and pivotal mounting to occupy various positions to one side or the other of the receptacle; spaced detents on the bail between which the hinge member can pass, and being selectively co-actable with the hinge member to support the cover in an upwardly and outwardly inclined position to one side and above the receptacle; and means on the hinge member co-actable with the receptacle to support the cover in an inverted and substantially horizontal position to one side of the receptacle when the cover is moved for the hinge member to pass between said detents.
